UNITED STATES PATENT OFFICE.

HARRY B. CLYATT, OF GRAND RAPIDS, MICHIGAN.

ANTENNA.

Application filed November 28, 1924. Serial No. 752,733.

The present invention relates to wireless communication utilizing an aerial for the interception of radio frequencies which are converted into audible signals and it is the purpose of the present invention to obtain better reception of the high frequency waves on a short aerial, and this is accomplished by the addition of capacity elements to the antenna wire.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a top plan view of a length of antenna embodying the invention,

Figure 2 is an edge view thereof,

Figure 3 is a plan view of a modification,

Figure 4 is a side view of the modification shown in Figure 3,

Figure 5 is a side view of a modified form of antenna consisting of a wire provided with pendants each carrying a plurality of capacity elements, and

Figure 6 is a sectional view taken on the plane indicated by the line 6—6 of Figure 5, looking in the direction indicated by the arrows.

Corresponding and like parts are referred to in the following description and designated in the several views of the drawings by like reference characters.

Referring to Figures 1 and 2, the numeral 1 designates a metal ribbon which may be of any length and width, and which is provided at one end with a snap hook as indicated most clearly at 3 in Figure 2. A plurality of capacity elements 4 are mounted upon the ribbon 1 and may be spaced apart any determinate distance as may be found most advantageous, and these elements consist of cylinders of thin sheet metal having

their sides corrugated in a spiral or helical form substantially as indicated, said elements being mounted upon the metal ribbon and made fast thereto by means of screws 5.

In the modification, the numeral 6 denotes a short length of metal ribbon having capacity elements 4 mounted thereon and projecting alternately from opposite sides as indicated most clearly in Figure 4, said capacity elements being attached to the metal ribbon by means of bolts 7 or analogous fastening means. One end of the metal ribbon 6 is formed into a roll 8 and the opposite end has an eye 9 applied thereto, and which is adapted to receive an antenna wire 10 upon which the capacity element equipped strips or metal ribbons 6 are strung and equally spaced, as shown most clearly in Figure 5.

What is claimed is:

1. An aerial provided in its length with unit elements, said unit elements consisting of sheet metal cylinders having their sides formed with spiral or helical corrugations.

2. An aerial comprising a ribbon having unit elements applied thereto and projecting from the sides thereof in various directions, said elements consisting of sheet metal cylinders having their sides formed with corrugations.

3. An antenna, elements loosely strung on the antenna and unit elements projecting laterally from the pendant elements strung upon the antenna, said elements consisting of sheet metal cylinders.

4. An aerial consisting of an antenna wire, metal strips strung upon the antenna wire and maintained in determinate spaced relation, and unit elements carried by said strips and projecting laterally from opposite sides thereof in alternation, said elements consisting of sheet metal cylinders.

5. An aerial comprising a ribbon antenna, unit elements generally of tubular form, said elements at one end having spaced flanges, said elements being threaded on said ribbon and extending in various directions and having said flanges overlapping the ribbon to maintain them in place.

In testimony whereof I affix my signature.

HARRY B. CLYATT.
